UNITED STATES PATENT OFFICE.

CHARLES MARIUS MOTTE, OF PARIS, FRANCE.

PROPELLER FOR VESSELS.

1,408,765.

Specification of Letters Patent. Patented Mar. 7, 1922.

Application filed April 12, 1920. Serial No. 373,361.

To all whom it may concern:

Be it known that I, CHARLES MARIUS MOTTE, a French citizen, residing at Paris, in the French Republic, have invented new and useful Improvements in Propellers for Vessels, of which the following is a specification.

This invention is an improvement in ships' propellers of the continuously revolving 10 turbine type with turnable casing, and it consists in the construction and combination of means forming a pair of co-acting suspended circular and symmetrically disposed turbine casings each with top and bottom 15 inlet ports and a single lateral eduction port; power-means for simultaneously and uniformly driving the turbine wheels; and controlling means for turning the turbine casings symmetrically in opposite directions to one another to thereby utilize 20 the eduction currents for driving and stopping the ship.

According to my invention I provide a pair of suitably divided surrounding turbine casings each having internal flanges to 25 form a circular channel, opening into the aforesaid eduction port, in which a plurality of radial blades or vanes are caused to circulate by the rotation of a suitably 30 driven turbine shaft. I also provide readily operated reliable gear for setting, changing or adjusting the direction of the eduction port.

It is my object to provide a self-contained 35 mechanism adapted to replace the usual screw-propeller and which, by continuous uniform rotation and without additional or extraneous parts, will serve for driving ahead and astern, slowing down and stopping a ship or boat.

This object I attain by the means illustrated in the annexed drawings as being the preferred embodiment of my invention.

In these drawings, Figure 1 is a vertical 45 central section of one of the suspended turbines, the operating mechanism being omitted for the sake of clearness.

Fig. 2 shows in elevation the arrangement of combined turbines for propelling vessels; 50 Figs. 3, 4 and 5 are plan views showing the important positions for the forward, and

rearward movement of the vessel and for stopping same by the turning of the eduction port.

Referring to Fig. 1, *a* shows radial blades 55 driven by a central shaft *c* so as to circulate in a circular channel formed by inwardly projecting flanges *b*^x provided in a suitably divided casing *b*. The casing *b* has inlet openings *b*¹ and *b*² at top and bottom while 60 a single lateral eduction port *d* is provided in the otherwise closed turbine casing. The casing *b* is rigidly attached at the stern of the ship to a tubular suspension body *e* which provides internal bearings for the 65 shaft *c*. The body *e* is suitably carried in a socket *f* rigidly fixed to the vessel to be driven by the turbine. The shaft *c* is constantly driven at proper speed by mechanism, such as mitre wheels or the like fast 70 on shafting connected with a motor.

As shown in Fig. 2 I arrange two turbines to work together, their driving mechanism being enclosed in protecting casings *f*¹. Independent of the inner revolution of the 75 turbine vanes *a*, it is necessary to provide gear for turning the turbine casing *b* in order to set the eduction port *d* at the various angular positions required for controlling the vessel, in going ahead or astern, 80 slowing down or stopping. For the relative angular displacement of the eduction port of both turbines arranged as in Fig. 2, I may provide co-acting chain drives *g* operating chain wheels *h* fast on the upwardly protruding body *e* connected with the turbine casing *b*, said chain drives being operated by chain pinions *h*² through the intervention of gear wheels *h*³, *h*⁴. The shaft of one of these gear wheels say, that of *h*⁴, is journaled in a sleeve fast on the casing *f*¹ and is controlled by a hand crank *i*. Thus, in turning said crank *i* the eduction ports of 85 both turbines turn in opposite directions through a corresponding angular space to 90 each other. The arrangement of the divided enclosing casing with internally flanged circular channels for the turbine blades gives great efficiency to the turbine, insures ready and plentiful access for the inflow to 95 the central part of the turbine casing and a strong eduction current through the

angularly disposed eduction port so that a vessel fitted with a pair of such turbines can be driven fast or slow and stopped easily and securely by the force and direction of the eduction currents.

I claim:—

Self-contained mechanism for driving and stopping ships through the intervention of

eduction currents, which consists in two similar suspended eduction devices, means 10 for producing eduction currents, and means for symmetrically varying the direction of eduction within circular and oppositely turning paths.

CHARLES MARIUS MOTTE.
